UNITED STATES PATENT OFFICE

2,263,873

CARGO WINCH

John Frederick Grunbeck, Seattle, Wash.

Substituted for abandoned application Serial No.
252,370, January 23, 1939. This application
June 3, 1940, Serial No. 338,543

1 Claim. (Cl. 254—145)

This invention relates to improvements in steam or electric powered hoists or cargo winches particularly adapted for use on shipboard, and is a substitute for application Serial No. 252,370, filed January 23, 1939, which became abandoned May 15, 1940. The principal object of the invention is to provide a hoist of this character in which two or more drums are used, one for hoisting or lowering the cargo boom and the other for the cargo fall, also the provision of safe and efficient means for hoisting or lowering the cargo boom and for maintaining it in any of its adjusted positions.

In hoists now common aboard ship only one drum, namely the cargo fall drum, is employed and it must serve the double purpose of first positioning the boom to any desired position and then to raise or lower the cargo by means of the usual hoisting cable. In order to use the single drum for hoisting or lowering, or otherwise positioning the cargo boom, it is necessary to first remove the cargo cable from the drum and then attach to the drum, or gypsy, the cable that controls or operates the cargo boom. After the boom is positioned the cable is removed from the drum or gypsy and then secured to a mast or other point of anchorage by any suitable means. This old method is unsafe and consumes considerable amount of time on the part of the workmen.

With my new and improved type of multi-drum hoist I overcome the foregoing objectionable and dangerous features by providing a secondary or supplemental drum adapted to be selectively operated independent of the main drum, and also providing means for locking the secondary drum to maintain the cargo boom in any operative position. I also provide means for securely locking the secondary drum to prevent its reverse rotation in a boom-lowering direction.

These and other objects will appear as my invention is more fully hereinafter described in the following specification, illustrated in the accompanying drawing and finally pointed out in the appended claim.

In the drawing:

Figure 1 is a side elevation of a mast, a cargo boom swingably mounted to the mast, and my new and improved hoist in operative connection with said mast and boom.

Figure 2 is an enlarged top plan view of the hoist.

Figure 3 is an enlarged detail view of a safety means in the form of a pawl and ratchet associated with the secondary drum.

Referring now more particularly to the drawing:

Reference numeral 1 indicates the base of the hoist to which are mounted two companion steam engines 2 and 3, supplied with steam from any convenient source of supply and controlled by a throttle valve 4, by means of a throttle arm 5. The connecting rod 6 of the engine 2 connects as at 7 with a crank 8 secured to one end of a drive shaft 9. To the opposite end of the drive shaft is secured a crank 10 which is operatively connected with the connecting rod 11 of the engine 3. Thus, as the engines are operated the shaft 9 will be caused to rotate. Slidably mounted upon the shaft 9, but engaged for rotation therewith by means of a key or a square on the shaft 12, are driving gears 13 and 14. The gears are spaced apart and united with each other for rotation as a unit by means of a sleeve 15, also slidably on the shaft 9, but rotatable therewith by means of the key 12 or a square on the shaft. Any suitable form of yoke 16 embraces the collar 15, and is adapted to slide or shift the same laterally on the shaft 9 by any suitable form of handle 17 extending upwardly from the yoke.

Mounted upon the base 1, in suitable bearings 18 and 19, is a main drum 20, provided at one of its ends with a gear 21 which meshes with the driving gear 14. The gear 14 is slidably transversely with respect to the gear 21. Also mounted upon the base in suitable bearings, 22, is a secondary drum 23, provided at one of its engagement with the driving gear 13. The opposite end of the drum 23 is formed with a braking surface or brake drum 25, embraced by a brake band 26, which is operable by a hand wheel or any other suitable leverage means 27 whereby the brake band may be applied to or released from the brake drum. On the outside of the brake drum is a ratchet wheel 28 adapted for engagement with a pawl 29, which may be secured to any fixed member of the machine. In Figure 3 I have illustrated the pawl as being carried by an arm 30, secured to the bearing 22.

Operation

In Figure 1 the cargo boom is indicated at 33 and is shown in full lines in an idle or non-operating position. The winch fall or runner 34 is shown extending from the main drum 20 out over a sheave 35, thence outwardly to the end of the boom over blocks 36, and terminating in any suitable type of hook or other cargo engaging means 37.

One end of a topping lift 38 is secured as at 39 or near the outermost end of the boom 33. The topping lift extends over a sheave 40 at or near the top of a mast 41 and extends down along the mast and through a clamping means 42. The end of the topping lift below the clamping means passes through a lead block 42A and is permanently secured on the secondary drum 23.

When it becomes necessary to raise the cargo boom into an operative position as shown in dotted lines, the clutch lever 17 is placed in such a position that pinion 13 engages gear 24 and at the same time disengages pinion 14, which is a part of the sleeve 15, from the driven gear 21 of the main drum 20. The clamping gear 42 is then released, engines 2 and 3 are set in motion, revolving the topping lift drum 23 and allowing the cargo drum 20 to remain free. Such rotation, of course, causes the cable 38 to wind around the drum with a resultant lifting of the boom 33. When the boom has reached its operative or loading position, the pawl 29 having engaged with one of the teeth of the ratchet wheel 28, prevents a reverse rotation of the drum 23, or the unwinding of the cable therefrom. Following this, the brake handle 27 is actuated to apply the brake 26 to the drum to further prevent any accidental reverse rotation of the drum. The clamping device 42 is secured, and the clutch lever is then shifted to disengage the topping lift drum gear 13, from gear 24 and to engage gear 14 with gear 21 on the main drum 20. The winch is then prepared to handle cargo in the usual way. After the loading operation is finished and the main drum 20 ceases to operate and it becomes desirable to lower the boom 33 into an idle position, the topping lift drum is again engaged by shifting the clutch lever 17, as described above, the pawl 29 and the clamping device 42 are manually disengaged, the brake 25 is slackened off and the boom 33 is lowered to rest

under control of the engines 2 and 3. In the event of steam not being available, the boom may be lowered under control of the brake 25. In the absence of the brake 25, the drum 23 under the pulling load of the cable would, of course, freely rotate with a resultant abrupt dropping of the boom. But by applying the brake to the drum at the same time the boom reaches its operative position, the drum is prevented from reverse rotation upon release of the pawl 29.

While I have shown a particular form of embodiment of my invention I am aware that many minor changes therein will readily suggest themselves to others skilled in the art without departing from the spirit and scope of the invention. Having thus described the invention, what I claim as new and desire to protect by Letters Patent is:

In a hoisting apparatus, including a mast, a cargo boom swingably mounted with respect thereto, a topping lift cable for actuating said boom, and a winch fall associated with said boom; a main drum having one end of said winch fall attached thereto, a secondary drum in spaced parallel relation to said main drum and having one end of said topping lift connected thereto, a driven gear fixed to one end of said main drum and a driven gear fixed to the opposite end of said secondary drum, a drive shaft between said drums and parallel thereto, a unitary driving gear means for both of said drums, said unitary gear means being longitudinally slidably mounted on said shaft and rotatable therewith, means for selectively moving said gear means out of engagement with one of said gears and into engagement with the other and vice-versa to separately actuate said drums, and means for rotating said shaft.

JOHN FREDERICK GRUNBOCK.

CERTIFICATE OF CORRECTION.

Patent No. 2,263,873.

November 25, 1941.

JOHN FREDERICK GRUNBOCK.

It is hereby certified that error appears in the printed specification of the above numbered patent requiring correction as follows: Page 1, second column, line 34, strike out "ends with a driven gear 24, adapted for selective" and insert the same after "its" in line 32; and that the said Letters Patent should be read with this correction therein that the same may conform to the record of the case in the Patent Office.

Signed and sealed this 5th day of May, A. D. 1942.

(Seal)

Henry Van Arsdale,
Acting Commissioner of Patents.
